UNITED STATES PATENT OFFICE.

JOHN B. WINTERS, JR., OF AVERY ISLAND, LOUISIANA.

PACKAGE-HANDLING TOOL.

1,247,918.

Specification of Letters Patent. Patented Nov. 27, 1917.

Application filed February 20, 1917. Serial No. 149,820.

To all whom it may concern:

Be it known that I, JOHN B. WINTERS, Jr., a citizen of the United States, residing at Avery Island, in the county of Iberia and 5 State of Louisiana, have invented a new and useful Package-Handling Tool, of which the following is a specification.

This invention relates to tools for handling packages such as canned goods, boxes 10 of cereals, and the like, whereby they can be removed readily from shelves out of the ordinary reach of a person, the said tool being light and durable in construction and easy to operate, there being means thereon for 15 gripping a package securely so that it will not fall while being conveyed.

With the foregoing and other objects in view which will appear as the description proceeds, the invention resides in the combination and arrangement of parts and in the details of construction hereinafter described 20 and claimed, it being understood that changes in the precise embodiment of the invention herein disclosed, can be made within the 25 scope of what is claimed, without departing from the spirit of the invention.

In the accompanying drawings the preferred form of the invention has been shown.

In said drawings:

30 Figure 1 is a front elevation of the tool.
Fig. 2 is a side elevation thereof.

Fig. 3 is a perspective view of the gripping head.

Referring to the figures by characters of 35 reference 1 designates an elongated shank preferably of wood and which is provided with oppositely extending bearing elements 2 in the form of staples or eye screws. In these bearing elements are journaled rods 3 40 which extend longitudinally of the shank and are provided at one end with angular extensions 4 forming grips. The other ends of the rods are bent inwardly over the adjacent end of the shank 1 and are looped to 45 provide eyes 5 and gripping arms 6. The eyes 5 fit one within the other so as to hold the arms 6 against movement away from each other without, however, interfering

with the free movement of said arms about an axis extending longitudinally of the 50 shank. The rods 3 and the arms 6 are formed preferably of heavy spring wire so that during the operation of the tool the arms 6 are free to yieldingly grip an object placed therebetween. 55

In using the tool the same is elevated until the arms 6 are brought adjacent opposite sides of the article to be removed from the shelf. The grips 4 are then swung toward each other so as to cause the arms 6 to move 60 toward each other and bind against opposed portions of the article. By holding the two grips in the fingers of one hand the tool can be readily lowered without danger of dropping the article gripped between the arms 6 65 and the pressure of said arms upon the article will be sufficient to hold it without the necessity of puncturing or otherwise injuring the package.

What is claimed is:—

1. The combination with a shank, of rods 70 extending longitudinally of the shank and connected thereto, said rods being mounted for rotation, a grip at one end of each of the rods and radiating therefrom, interfitting eyes at the other end of the rods and extending over one end of the shank, and article engaging arms extending from the eyes. 75

2. The combination with a shank, of rods 80 extending longitudinally of the shank and connected thereto, said rods being mounted for rotation, a grip at one end of each of the rods and radiating therefrom, interfitting eyes at the other end of the rods and 85 extending over one end of the shank, and article engaging arms extending from the eyes, each of said rods with its grip and arm being formed in a single length of spring wire.

In testimony that I claim the foregoing as 90 my own, I have hereto affixed my signature in the presence of two witnesses.

JOHN B. WINTERS, JR.
